UNITED STATES PATENT OFFICE

EDWIN FITCH NORTHRUP, OF PRINCETON, NEW JERSEY, ASSIGNOR TO AJAX ELECTRO-THERMIC CORPORATION, OF AJAX PARK, NEW JERSEY, A CORPORATION OF NEW JERSEY

WINDING FOR ELECTRIC FURNACES

Application filed June 5, 1928. Serial No. 283,035.

My invention relates to the art of inductive electric furnaces in which there is danger of leakage of molten metal through the furnace refractory.

- 5 One purpose of my invention is to automatically give warning or cut off the power supply when the molten furnace content has broken through the refractory about it to any predetermined extent.
- 10 A further purpose is to give an alarm or to cut off the power supply from the inductor coil of an induction electric furnace when leakage flow of molten metal has altered the condition of an electric circuit by which the
- 15 furnace is protected.

A further purpose is to provide a protective electric circuit about the side or bottom walls retaining a mass of molten metal, or about both in such relation that penetration of 20 the molten metal through the refractory as far as the circuit will short-circuit or open this circuit, thereby giving an alarm or shutting off the power from the furnace.

A further purpose is to protect the inductor 25 coil of an induction electric furnace and to protect the operators from injury by molten metal breaking through from the molten content.

A further purpose is to introduce a protective electric circuit between the metal and the inductor coil of an electric furnace with 30 heat insulation on both sides of the circuit as a means of giving warning or checking the flow of electric current through the furnace when the melt has started to leak through the refractory.

A further purpose is to provide an electric circuit surrounding a pool of molten metal with a balanced outer circuit which is unbalanced by the effect of the molten metal and when unbalanced gives visual or audible indication or shuts off the current for protection of the furnace.

45 A further purpose is to provide an electric circuit which protects a furnace from leakage damage with an outside circuit having indicators distributed in different parts of the circuit indicating short-circuit or open 50 circuit or normal condition of circuit.

Further purposes will appear in the specification and in the claims.

My invention relates to the method or processes involved as well as to apparatus by which they may be carried out.

I have preferred to illustrate my invention by variations of one main form only among many forms in which it might appear, selecting a form which is practical, efficient, simple, reliable and inexpensive and which at the same time well illustrates the principles of my invention.

Figure 1 is a vertical central section over a water-cooled inductor furnace, having a protective winding capable of carrying out my invention.

Figure 2 is a vertical central section through an air-cooled inductor furnace, showing a slightly different arrangement of the protective winding.

Figure 2^a is a fragmentary section similar to Figure 2, showing refractory only and varying slightly from Figure 2.

Figure 3 is a diagrammatic illustration of an electric circuit including a protective winding.

Figure 4 is a diagrammatic view somewhat similar to Figure 3, but showing a different arrangement of indicators or current interrupting mechanism in the circuit.

Figure 5 is a diagrammatic view applying Wheatstone bridge connections.

Figure 6 is a diagrammatic view applying Wheatstone bridge connections with a current interrupting mechanism.

In the drawings similar numerals indicate like parts.

In all furnaces handling molten content and in all refractories holding molten metal the refractory progressively deteriorates. For this reason as well as because of occasional breakage of solid refractories there is constant danger of leakage of the molten metal.

While my invention is therefore of value in all such furnaces it finds its greatest need and hence its greatest utility in electric furnaces of the induction type free from inter-threading of transformer iron and in which the inductor surrounds the furnace pool.

In such furnaces it is necessary to have the diameter of the metal as large in proportion to the total diameter of the coil interior as possible to improve the coupling. The necessity for close coupling between the pool and coil reduces the spacing for refractory to a minimum, increasing the danger of short-circuiting of the coils by leakage of the metal.

This short-circuiting may be highly injurious to the inductor coils even with air-cooled coils, but in the case of water-cooled coils involves the further danger of melting the metal of the coils and allowing water from the coils to engage the molten metal, possibly resulting in explosions which are dangerous both to the operators and to the apparatus.

I find that complete protection can be obtained against failure of insulation by cutting of the power input, or partial protection may be had by warning, for any predetermined extent of failure of insulation and consequent leakage at any point or over any area desired. I secure this protection by locating an exploring winding about the furnace or within the refractory where protection is desired, usually covering by the winding the entire space between the molten metal and the inductor coil to fully protect the latter, or I may completely surround the sides and bottom of the molten metal pool if desired.

When the invention is applied to a furnace having a pool-surrounding inductor coil my invention contemplates protecting the lateral sides and if desired also the bottom of the electric furnace pool by an exploring coil connected in an electric circuit, so that leakage of molten metal beyond the confines of the pool to a depth determined by the spacing of the exploring coil from the molten metal will cause alteration in the characteristics of the exploring circuit. The open circuit or short circuit produced is used to operate an alarm or relay, permissibly warning of the danger or cutting off the energy supply from the furnace or both.

As will be seen, the broad invention is independent of the character of the exploring coil, of the nature of the connection by which signal operation or power interruption is secured, and of the detail of the furnace itself. It is my understanding that I am the first to make use of an exploring coil for any such purpose in any furnace and that I am the first to protect against refractory failure electrically by any signal, alarm or supply current interruption. For the above reason in application to the broad invention I have intended my drawings to be diagrammatic and illustrative merely of structure by which my invention may be carried out. In so far as I have shown furnace structure at all, I have chosen my illustrations for the purpose of making my meaning more clear and not with

the thought of showing extremes or limits to which the invention is applicable.

I show in Figures 1 and 2 two forms of exploring coil, which differ in direction of winding but which do not differ in the least in theory of operation.

In the furnace in Figure 1 I have illustrated a water-cooled inductor coil 10 free from interthreading with furnace or transformer iron and spaced from the melt 11 by a refractory. I have intended to illustrate a furnace free from complication and comprising a crucible 12 surrounded by a water-cooled hollow inductor coil 13 whose electrical connections are shown at 14, 15 and 80 whose water-cooling inlet and outlet connections are shown at 16 and 17 respectively.

Within the water-cooled furnace inductor coil 13 I provide a protective cylinder 18, which is desirably strong enough mechanically and heat resistant enough to stop a flow of molten metal directed toward the coil until an electric alarm can be answered or until automatic cut-off of the current from the inductor coil will have been effective to chill 90 the furnace and to thus retard or stop leakage flow of the molten metal.

This protective cylinder 18 may be the regular cylinder which electrically insulates the inductor coil or a special cylinder, of any 95 suitable material and desirably extends to a point below the inductor coil. It may seal at the bottom with a sand or other suitable base for the crucible or with a bottom for the melt where no crucible is used. Between the cylinder 18 and the melt I provide sand or other heat insulation desired. Here the melt is illustrated as lying within a crucible.

Within this space I mount my exploratory coil, loop or other screen winding it non-inductively where the furnace has an inductor coil but otherwise without the same need of care in this particular. The source of current can be direct or alternating and of any voltage for which the circuit is suited. The 110 winding can be of insulated or uninsulated wire.

With additional heat insulation a choice of location is offered and the "coil", as my screen will be called for convenience, may be located along the inner surface of the heat insulation, along its outer surface or within the body of or between parts of the heat insulation, depending upon the distance from the crucible at which it is desired to have the exploratory coil operate and upon the question of how much protection against further flow of molten metal is to be provided in the direction of its flow and beyond the exploratory coil.

I find that it is quite convenient to mount the exploratory coil upon a cylinder or frame 19 which may itself form a part of the heat and electrical insulation. The wires of the 130

coil may be separately insulated or may take their insulation from the cylinder 19.

In Figure 1, as suggested the exploratory coil is not desirably wound inductively because in that case current will be induced in it and therefore in its circuit from the main inductor coil as a primary in excess of the current which should be needed for this circuit, reducing the efficiency of the main inductor coil and at the same time defeating the purpose of the exploratory coil by the excessive current flow in the circuit of the exploratory coil. The exploratory coil is therefore wound non-inductively wherever induction would occur. It is wound differently in the forms shown in Figures 1 and 2 and may, obviously, be wound in many other different ways.

In Figure 1 the coil comprises a length doubled upon itself to form a loop 21 and 22. The two sides are wound side by side around the support or cylinder 23, in ring form producing a winding much like that of a Gramme ring. The distance between adjoining double wires 24 is small enough to prevent flow of any appreciable amount of leakage molten metal between one loop pair and the next without opening the circuit by melting the wire or causing a short circuit between the adjoining portions of the double winding.

The otherwise open ends of the double winding are connected to a source of energy through an indicator or relay, so that either opening the circuit or short-circuiting the wires of the coil will operate an alarm, if alarm only be desired, or will cut off the current from the inductor coil of the furnace so as to prevent further injury to the inductor coil or to the individuals or apparatus about it.

In the form shown in Figure 2, the inductor coil 13' is air-cooled, the furnace is of slightly different form and the exploratory coil is differently wound.

The air-cooled coil 13' is free from the danger of explosion present with the water-cooled coil but still presents the same danger to supply apparatus in case of short-circuiting.

The difference in the furnaces is shown deliberately for the purpose of emphasizing the fact that the use of a crucible or the non-use of a crucible, makes no difference in the application of my invention. The pool 11 here lies within an internally sintered refractory 20. The lining is effected by the initial use of a protective cylinder corresponding in outside diameter with the inside diameter of the furnace wall 21 and covering it outside and filling it in at the bottom with a suitable sand or resting it upon a sand bottom so that sintering takes place before destruction of the protective cylinder, leaving a sintered surface at 21 and at the bottom 22, which is effective

to hold the melt. It is not my intention to claim this method of production of the lining form here.

The winding 23, 24 is non-inductively wound about a cylinder 18 outside of the refractory lining and between this refractory lining and the inductor coil.

In Figure 2^a the winding 23, 24 is shown as located within the refractory and as protecting the bottom as well as the sides—a protection which is easily added but which will ordinarily not be required because it is needed less and can be provided easily in other ways.

The refractory of Figure 2^a may be a solid refractory as in Figure 1, within which the winding is encased during manufacture, or a loose refractory as in Figure 2. I have illustrated temporary means only for supporting it as in either case it would be supported by the refractory. In principle it would not matter whether the temporary support baked out during baking of the refractory or use of the furnace or remained in.

Instead of a Gramme ring winding as seen in Figure 1, the windings in Figures 2 and 2^a are helical windings having vertical axes.

Where it is desired to protect the inductor coil only, as where other forms of protection for the bottom are available, such as leakages claimed by me in another application, or are not regarded as necessary, no exploratory coil protection for the bottom is provided. Where such a protection is desired it is easily secured in any form by continuing the lower end of the non-inductive helical winding in the form of a double pancake spiral within or beneath the bottom refractory as in Figure 2^a.

The winding is placed within the refractory where it is desired that the exploratory coil shall give warning or shall operate to shut off the current with leakage of molten metal through a part only of the main refractory, as distinguished from the leakage through substantially the entire main refractory until the heat was sufficient to melt or the metal short-circuits as would be necessary in the forms of Figures 1 and 2.

I recognize that the exploratory winding need not be a coil in the usual acceptance of that term but can be any system, network or arrangement of conductors which covers at not too great intervals the areas to be protected and which will reliably vary in resistance sufficiently for operation of an indication or a relay when molten metal approaches it or flows upon it. I recognize also that a refractory-encased exploratory winding can be encased within a loose refractory or within a solid refractory, baked or otherwise, such, for example, as a crucible.

Whatever the form of application of the exploratory winding for the furnace, it is the intention to connect it with an outside circuit including a source of energy and an indi-

cator or indicators, or a relay or other operating mechanism, so that short-circuiting or opening the circuit or a considerable change of resistance of the circuit containing the exploratory winding becomes effective to operate the desired signal or cut off the current, or perform such other function as may be predetermined for the protection of the furnace. It will be noted that the winding, the circuit with the winding, the signal and the current interruption are all protective devices for the furnace though the latter only is automatically corrective.

Not only may the forms of furnace and the exploratory winding or screen used with it be greatly varied as indicated, but it will be obvious that the variety of types and arrangement of protector whether indicator or current-interrupting mechanism may also be greatly varied to render the variation in exploratory winding resistance effective for the purpose indicated.

Among the many arrangements of circuit which would be effective with the type of exploratory windings shown I have illustrated four diagrams only of external circuit arrangements.

In Figure 3 the two sides of the loop exploratory winding are shown as comprising the two sides 25 and 26 of circuit connected to a line 27 or other suitable source of current of any desired voltage, direct or alternating, generator or battery. The circuit is shown as containing a signal of one character or in one position such as a red light 28 in series with one of the sides and a signal of another character or in another position such as a white light connected in series between the two sides.

With the connection shown the source of current is such that in normal operation both lights burn dimly. In case of short circuit as diagrammatically indicated at 30, through a flow of molten metal or because of heat-charring of insulation by the molten metal, the red light will burn brightly and the white light will go out.

On the other hand if the circuit be opened, due, for example, to melting of the conductor, as at 31 both lights will go out. It will be noted that in either event abnormal conditions cause the current through signal 29 to fail so that evidently a single signal at this point will suffice; since it matters little whether the circuit be open or be short-circuited. This signal may be visible, audible, tangible or otherwise sensitory. Moreover, as seen in Figures 4 and 5 it could be replaced by an operating mechanism for an inductor-coil-circuit disconnecting switch.

It is obvious that this is but one of many arrangements for grouping signalling devices so as to indicate abnormal circuit conditions.

In the form shown in Figure 4 the ends

of the winding are relatively reversed for the connections made so that the end A of one of the double wire windings is connected to the end B of the other and the ends C and D of the two windings are connected, in each case however through coils. This reversal is intended to maintain substantially the same length of winding within the circuit in case of short circuit, wherever that short circuit take place avoiding possibility of but slight variation in resistance if short circuit take place near the ends of the winding parts.

The double windings are used to avoid induction and need not be used where no other winding is used which could cause objectionable induction.

I insert a resistance 32 in series with one of the double windings to insure that there will be a predetermined resistance in the circuit in the case of short circuit. I connect the two sides of the source of current through a coil 33 preferably engaging the resistance 32 at an intermediate point and connect the ends A and B through a coil 34. The coils 33 and 34 may comprise oppositely operating coils of a differentially wound electric magnet which will operate a signal of any character such as is shown in Figures 3 and 5 or will operate a galvanometer indicator to close a relay circuit at opposite ends of its stroke or will operate or release a shutter to energize a relay circuit, using the relay for signalling purposes or for interruption of the main power supply. I have not considered it necessary to illustrate the signal or relay operation further because of the illustration of signals in Figures 3 and 5 and of relay current interruption in Figure 6.

In Figure 5 opposite ends of the two parts of the double winding are connected in series to form an unknown resistance 39 in series with any indicator or relay shown here as a white lamp utilizing the double winding and protective device as one leg of a Wheatstone bridge 29 whose other legs are represented by resistances 30, 31 and adjustable resistance 32. The place of the galvanometer of the usual form of the Wheatstone bridge is taken by a second protective device here shown as a red lamp. Any change in the resistance of the protective exploratory winding, either by opening the circuit or by short circuit of any part of it will show itself to the operator by variation in the indication of one or both of the protective devices.

As in Figure 4, the reason for the connection of the opposite ends of the two conductors forming the double winding of the exploratory coil lies in the desire to make short circuiting effective as much as possible, as otherwise in case of short circuiting close to the ends of the loop the effect upon the protective devices might be very slight and would require excessive delicacy of setting of the Wheatstone bridge.

Of course the difference in indicator is only one of many differences which might be made in the application of this invention even where a balance system is to be used and a change in a predetermined current flow or the unbalance of this or of any other balanced system could be used to open the circuit of the main power supply. This is seen in Figure 6.

In Figure 6 the place of the white lamp is taken by a solenoidal winding 40 effective upon an armature 41 to hold a switch lever 42 in an intermediate position. The lever is pulled in opposite directions by springs 43 and 44. The armature connects with the lever by a link 45.

In the neutral position the switch connects between terminals 46 and 47 of a relay circuit energized by battery 48 and including a solenoid 49 which lifts an armature 50 connected with a contact plate 51. When lifted the contact plate engages and closes terminals 52 and 53 of a main furnace circuit containing a generator 54, furnace coil 55. The power factor is corrected by capacity 56.

Variation of the current through solenoid 40, either to increase it or to decrease it will cause interruption of the relay circuit and hence of the main furnace circuit.

It will be obvious that the voltage of supply which may be necessary or advisable and the character or source of current are not material. In Figure 5 I have intended to indicate this by showing resistance 35 for the purpose of cutting down a supply of current of too high voltage to that voltage which may be desired for the purpose.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:—

1. In a furnace, a refractory holding molten metal, an exploratory electrically conductive winding about the molten metal, an electric circuit connected with the winding and a protective device in said circuit operative with alteration of resistance in the circuit due to refractory failure and molten metal effect upon the exploratory winding.

2. In an electric furnace, a refractory adapted to contain molten metal, a furnace winding surrounding a part of the molten metal, an electrically-conductive protective winding between the furnace winding and the molten metal and an electric circuit including said protective winding altered in re-

sistance for protective purposes by flow of molten metal due to refractory failure.

3. In an electric inductor furnace, a refractory adapted to contain a furnace pool, an inductor winding about the pool, an exploratory winding between the molten metal and the inductor, a source of energy in circuit with said winding and electro-magnetic protective means operated by said circuit for protecting against leakage of molten metal past the winding.

4. In an inductor electric furnace, a refractory adapted to hold a furnace pool, an inductor coil surrounding the refractory, an exploratory winding between the pool and the coil adapted to be short-circuited or opened by reason of failure of the refractory, a circuit including the winding, a source of current in said circuit and a protective device in said circuit adapted to operate by reason of variation of current flow in said circuit due to refractory failure.

5. In an inductor electric furnace, a refractory adapted to hold a furnace pool, an inductor coil surrounding the refractory, an exploratory winding between the pool and the coil adapted to be short-circuited or opened by reason of failure of the refractory, a circuit including the winding, a source of current in said circuit and signalling or interrupting means operated by said circuit for signalling or opening the inductor current supply with variation in said current.

6. In an induction electric furnace, a refractory adapted to hold a pool of molten metal, a liquid-cooled inductor coil surrounding said pool, a protective winding between the pool and coil located within the refractory, a circuit including the winding, and a protective device in said circuit operative with variation in the current through the winding circuit.

7. In an induction electric furnace, a refractory adapted to hold a pool of molten metal, an inductor coil surrounding said pool, a non-inductive protective winding between the pool and coil located within the refractory, a circuit including the winding, and a protective device in said circuit operative with variation in the current through the winding circuit.

8. In a furnace, a refractory, a non-inductively wound exploratory winding about the refractory, an electric circuit connected with the coil and a protective device in said circuit operative with alteration of resistance in the circuit due to refractory failure and molten metal effect upon the refractory winding.

9. In an electric furnace, a refractory adapted to contain molten metal, a furnace winding surrounding a part of the molten metal, a protective winding non-inductively wound between the furnace winding and the molten metal and a circuit for said protective winding altered by alteration of the resist-

ance of the protective winding for protective purposes.

10. The process of protecting an inductor coil from injury by molten metal enclosed within it which consists in normally maintaining a flow of electric current at interval points across the space between the pool and the coil and in causing a variation in said current to give warning of refractory failure or stop the flow of current in the inductor coil.

11. The process of warning or stopping the current flow in an inductor circuit with failure of insulation about a furnace pool within the inductor which consists in causing flow of molten metal due to refractory failure to vary an electric current and indicate the injury or stop the inductor current flow.

12. The process of protecting against failure of refractory about molten metal which consists in utilizing the flow of the metal itself with partial failure of refractory to indicate the failure of the refractory by variation of electric current.
